UNITED STATES PATENT OFFICE.

AUGUSTINE D. WAYMOTH, OF FITCHBURG, MASSACHUSETTS.

LATHE.

SPECIFICATION forming part of Letters Patent No. 397,528, dated February 12, 1889.

Application filed July 18, 1882. Serial No. 67,074. (No model.)

To all whom it may concern:

Be it known that I, AUGUSTINE D. WAYMOTH, a citizen of the United States, and a resident of the city of Fitchburg, Worcester county, in the Commonwealth of Massachusetts, have invented certain new and useful Improvements in Lathes, more especially adapted for turning wood, of which the following, taken in connection with the accompanying drawings, is a specification.

One part of my said improvement consists in constructing the carriage which supports the rest, tool-holder, &c., adjustable in its relation to the guides or ways upon which it slides, in order that the requisite compensation for wear of the engaging parts may be made by the operator.

Another part of my invention consists in constructing the tool-holder in such a manner that the holder, and thereby the tool, may be moved to and from the axial line of the article operated upon without change or adjustment of other parts supporting the tool-holder.

Another consists in the employment of a rack and pinion, forming a part of the lever-connection, in lieu of a disk, with crank-pins, for controlling the action of the "forming" and "cutting-off" tool, whereby a positive action of parts is at all times insured; and a further improvement consists in pivoting the open socket, which supports the roughing-knife at or near its rear end, upon a lower bed in such a manner as to be capable of a lateral or angular adjustment by means of appropriate mechanism at or near its forward or front end, whereby the proper slant of the tool may be regulated.

Referring to the drawings, Figure 1 represents a top view of my lathe. Fig. 2 represents a transverse vertical section. Fig. 3 represents a transverse vertical section of the lathe-bed, showing operative parts in position. Fig. 4 represents a section of the carriage and mode of its adjustment. Fig. 5 represents the tool-holder with its means for adjusting the holder and tool. Figs. 6 and 7 represent the open socket or roughing-tool holder pivoted to its support, showing the arrangement of the adjusting device for controlling the rake of the tool. Fig. 8 represents the rack

and pinion for connecting the knee-lever with the finishing and cutting-off tool holders. Fig. 9 represents a front view of the tool-holder shown in Fig. 5. Fig. 10 represents a section of a tool-holder shown in Fig. 6, and showing its manner of adjustment.

The lathe is provided with a head-stock, (represented at B,) a sliding carriage, (represented at C,) and a tail-stock, (represented at D,) which parts are arranged upon a suitable bed or frame, (represented at A.) To the carriage C and its immediate or more direct connections are applied the principal features of my improvements.

The carriage C is provided with "waves," which in this instance are represented as grooved, although the counterparts with which the carriage is intended to connect may be grooved instead, it being only a matter of convenience, as the operation of the parts would be the same constructed either way.

The drawings represent the ways, which form a part of the carriage, in two separate parts, (more clearly shown in Figs. 2 and 3,) secured to the lower part of the carriage proper, which supports the several elements which constitute the operative parts thereof in such a manner as to be capable of being spread apart when desirable to compensate for any wear of the engaging-surfaces, which is accomplished as follows:

The two ways 1 2 (which are adjustably supported in position) are moved outwardly when necessary by means of a wedge or wedges. In this particular instance, however, screws are employed with wedge-shaped or tapered ends, as shown in Fig. 4, which are placed above and act at the center or line of division between the two

in such a manner as to push them outwardly when the screw or screws are operated upon and the wedge part forced between. By this means I have secured a convenient, cheap, and effective adjustment, which cannot be so well accomplished by setting the outer ways

or guides inward, for the reason that the most wear occurs at the points of engagement with the carriage, whereas at the points of connection with the head and tail-stock little or no wear occurs, owing to the fact that the head seldom moves upon the ways and the tail-stock very little as compared with the car-

riage. Consequently it is impossible to secure the same results under all circumstances by the adjustment of the slides upon the bed.

The holder for supporting the finishing-tool 5 (more fully represented in Figs. 5 and 9 of the drawings) is pivoted or hinged to its support at *x*, and is adapted to be adjusted in a desired position in practice, so as to vary the contact of tool with the article being turned 10 by elevating or lowering its cutting-edge while the lathe is in operation, and also avoid the necessity of shimming. The means shown in the drawings for adjusting the tool-holder for the purpose indicated consists of a screw provided with a right and left hand thread, 7, and two threaded nuts, 5 and 6, pivotally connected to the tool block or holder 3 and its support 4, whereby the two parts are held in a desired position. By this arrangement 15 the operator is enabled to adjust by elevating or lowering the point or cutting-edge of the tool by simply turning the adjusting-screw 7 in the proper direction to secure the desired result. I would remark, however, 20 that this adjustment of the tool-holder may be effected by the application of a single-threaded screw, pivoted to either the tool-holder or its support, acting through an ear fixed upon the other, and provided with 25 two jam-nuts, or by a single nut operating upon the screw within a slot or between two ears, the chief object being to maintain a rigid connection of parts, and at the same time 30 permit of the proper adjustment of the cutting-tool while in operation, and avoid the necessity of "packing up" with thin strips of metal, &c., as is usual in cases without a similar adjustment. This tool-holder is pivoted to the sliding carriage before referred to, and 35 is shown in Fig. 2 of the drawings in position to be operated upon by the lever *e* through the medium of the rack-and-pinion connection 40 and 9. This rack-and-pinion connection is an improvement upon an invention for a like 45 purpose for which a patent was granted to me March 25, 1879, No. 213,718, the chief object being to avoid dead-centers. In other words, 50 the action of the rack upon the pinion causes the latter to move positively, regardless of the position of the relation of the pin (with which the pinion is provided) to its connecting-lever *h*. In practice it has been found that when 55 two pins are employed upon a disk and are caused to move into or very nearly into line with the connecting-levers they cease to operate readily, and sometimes stop upon what is sometimes termed their "dead-centers." The purpose, however, of these intermediary 60 connections is to impart the proper movement to the cutting-tools through the medium of the lever *e*, when desired, by the knee or otherwise. In lathes adapted for turning wood and other vegetable matter where a roughing-tool is required it has been found 65 desirable at times to not only adjust the tool to and from the axial line of the article being turned, but also to adjust and regulate the

rake of the cutting-edge so that it may cut more or less freely, and at the same time by such adjustment produce a natural feed motion to the tool and carriage without the aid of especial mechanism for that purpose. To this end I have improved upon my invention patented March 25, 1879, before referred to, by hinging or pivoting the open socket or 70 tool-holder *N* upon a ledge or flange. (Represented in the drawings at *O* in Figs. 4, 6, and 7.) This part *O* is pivotally connected with the face of the upright part of the carriage *C* in the particular instance by screw 80 shown by dotted lines at 15 in Fig. 7. This ledge *O* is adjustable upon its pivot and held in a desired position by a bolt or screw operating through a circular slot with which the upper part of the carriage is provided. (More 85 clearly shown in Fig. 6 of the drawings.) This tool-holder is also adapted to swing slightly to the right and left, being pivotally secured to the ledge *O* at or near the end opposite the cutting part of the tool, and an adjusting-screw, 12, is passed through an opening (more 90 plainly shown in Fig. 10 of the drawings) intersecting with a threaded lug forming a part of or rigidly fixed to the tool holder or socket *N*, which is somewhat narrower in width than 95 the length of the opening within which it is intended to move, which will be readily understood.

The ledge and holder being thus connected, the said holder and the tool which it carries 100 are adjusted in the desired direction by the adjusting-screw 12, referred to, and by this means the tool may be set at the proper angle to insure more or less free cut, and thereby increase or decrease the rapidity of the 105 feed motion of the carriage thus automatically produced by the rake or cut of the said tool.

It will be obvious to those skilled in the art 110 that the tool-holder may be adjusted upon the ledge by the application of two screws acting against a tongue or other suitable projection, or by other means having the effect to carefully adjust and rigidly hold the tool in the desired raking position to the right or left. 115

The application and arrangement of the several elements which together constitute 120 my improved lathe are so fully illustrated in the drawings that a further description would seem superfluous. I would remark, however, 125 that the several improvements herein set forth may be applied to any machine to which they or any of them may be adapted.

Having thus set forth my invention, what I claim as new, and desire to secure by Letters Patent of the United States of America, is—

1. In a wood-turning lathe provided with a chuck and a series of cutting-tools secured to a sliding carriage, the combination, with a pivoted tool-holder supported upon a ledge, of 130 an adjusting-screw whereby the tool may be given more or less lead, substantially as and for the purpose set forth.

2. In a wood-turning lathe provided with a

series of cutting-tools operating in combination with a sliding carriage, the combination, with one or more guideways for supporting said carriage, of one or more adjusting-screws adapted to force apart the said ways or guides, substantially as and for the purpose set forth,

3. In a wood-turning lathe, the combination, with a sliding carriage provided with a pivoted supporting-ledge carrying a tool-holder, of an adjusting-screw connecting with said holder and operating through a slot with which the carriage is provided, whereby the rake of the cutting-tool is passed, substantially as and for the purpose set forth.

15 4. The combination, in a wood-turning lathe, of a pivoted tool-holder, constructed substantially as described, with a clamping device provided with an overhanging flange

or oar adapted to hold the cutting-tool by contact with its side, and an adjusting-screw for changing the position of said tool-holder for regulating the slant of the cutting-tool, substantially as set forth.

5. In a wood-turning lathe provided with a chuck and sliding carriage and a series of cutters, the combination, with a jointed tool-holder capable of adjustment by means of a right-and-left-threaded screw, of a connecting rack and pinion, and operating-levers, such as described, whereby the cutting-tool may be adjusted while operating, substantially as and for the purpose set forth.

AUGUSTINE D. WAYMOTH.
